UNITED STATES PATENT OFFICE

2,438,663

FUEL INJECTION SYSTEM FOR INTERNAL-
COMBUSTION ENGINESLeonard Sidney Greenland, Weston-super-Mare,
England, assignor to H. M. Hobson Limited,
London, England, a company of Great BritainApplication December 29, 1945, Serial No. 638,130
In Great Britain February 12, 1945

6 Claims. (Cl. 123—119)

1

This invention relates to fuel injection systems for internal combustion engines of the type in which fuel is delivered under pressure to the engine, or to the induction system, through a main fuel conduit containing a variable area metering orifice, the effective area whereof is varied as a desired function of boost pressure, and preferably also of exhaust back pressure and induction temperature as well, and which includes means for maintaining across the metering orifice a pressure difference (hereinafter referred to as the metering pressure) which varies as a desired function of engine speed.

In a system of this character the metering pressure will be related to engine speed according to a definite law determined by the nature of the device for regulating the metering pressure and it is preferred to utilise for this purpose an engine driven centrifugal impeller, some fraction of the pressure difference developed by which is applied across the metering orifice. The metering pressure will, in this case, vary as the square of the engine speed.

On the fuel/air ratio determined by the device for regulating the metering pressure to accord with changes in engine speed in conjunction with the devices for correcting the area of the metering orifice in accordance with variations in the other variables above referred to, it is necessary however to superimpose additional corrections to suit specific conditions of engine working. Such corrections are required:

- (a) to provide slow running adjustment,
- (b) to give an enrichment in mixture strength from weak cruising to normal cruising,
- (c) to provide an enrichment in mixture strength during periods of acceleration.

According to the invention, three supplementary fuel conduits are provided, one being controlled by a slow running valve, one by a weak-to-normal enrichment valve and the third by an accelerator pump, and a single manually operable linkage controlled by the pilot's throttle lever is utilised to operate both valves and the accelerator pump to effect the aforesaid corrections automatically as an incident to adjustment of the position of said lever.

The conduit controlled by the accelerator pump will be arranged in parallel with the metering orifice, and the accelerator pump will operate to feed additional fuel to the engine through that conduit only when the pilot's lever is given a sudden movement to increase the engine power. The weak-to-normal enrichment valve may likewise control a conduit in parallel with the me-

2

tering orifice and in this case it will be closed for positions of the pilot's lever between slow running and weak cruising, and opened when the pilot's lever is moved into the normal cruising position or to a position selecting higher power from the engine than this. Alternatively, however, this valve may, as described in U. S. patent application Serial No. 533,120, now Patent No. 2,419,171, control a conduit for bleeding fuel from the entry side of the metering orifice, in which case it will be open only for positions of the pilot's lever selecting a power less than that required for normal cruising, and closed when the pilot's lever is moved to a position selecting higher power. The slow running valve may also control a conduit in parallel with the metering orifice, in which case it will be arranged to be opened only at slow running, and will enrich the mixture at slow running. In some cases, however, it may be desired to weaken the mixture at slow running. The slow running valve can then be disposed in a conduit for bleeding fuel from the exit side of the metering orifice and arranged to open only at slow running. As a further alternative, the slow running valve may, as described in U. S. patent application Serial No. 533,120, be employed to control a bleed pipe leading from the entry side of the metering orifice.

Preferably the linkage is arranged so as to actuate a fuel cut-off valve, when the pilot's lever is moved beyond the slow running position in the direction to reduce engine power.

In Figs. 1-4 of the accompanying drawings are shown diagrammatically four examples of fuel injection systems according to the invention intended for installation in aircraft engines. Like reference characters designate like parts throughout the figures.

Considering first the arrangement shown in Fig. 1, fuel is fed from an inlet 10 by an engine driven gear wheel pump 11 along a main fuel conduit 12 to a metering orifice 25 the effective area of which is controlled by a needle 24. The pump 11 is provided with a diaphragm-operated relief valve 33 in the usual manner, which valve is balanced to atmosphere in this particular case via a vent 34 behind the diaphragm 35. Thus the pump delivery pressure is maintained substantially constant in relation to atmospheric pressure, any excess fuel delivered by the pump being returned from conduit 12 to the suction side via pipe 36.

The pressure difference across the metering orifice 25 is arranged to be substantially proportional to the square of the engine speed utilising

the difference of pressure generated across an engine driven centrifugal impeller 37. The pressure at the tip of the impeller is applied via conduit 38 to the upstream side of the orifice and a desired proportion of the impeller eye pressure is applied to the downstream side of the orifice by means of a flexible diaphragm 39 operating a pressure regulating valve 40, as described for example in U. S. Patent No. 2,374,844. The left hand side of the diaphragm 39 is exposed to the impeller eye pressure via a conduit 44, while the right hand side is exposed to the fuel pressure at the exit of the metering orifice.

After passing the metering orifice 25, the metered fuel enters a chamber 19 and passes thence through the pressure regulating valve 40, pipe 45, and balanced discharge valve 46 to a nozzle 47 through which it is injected into the induction pipe 15.

The diaphragm 39 is coupled to the stem of the pressure regulating valve 40 by means of a bell crank lever 48 mounted on a fixed pivot 49. The diaphragm 39 is loaded by a spring 50 which serves to balance the forces exerted by the fuel on the pressure-regulating valve 40 and also to produce a pressure difference across a restricted orifice 43 through which air and vapour are vented from the eye of the impeller 37 to the downstream side of the metering orifice 25 as described in my copending U. S. application Serial No. 638,127, filed December 29, 1945.

The effective area of the metering orifice is varied as a desired function of boost pressure and exhaust pressure by a pair of balanced capsules 13, 14 disposed in the chamber 19. The capsule 13 is subjected to boost pressure internally, being connected to the induction pipe 15 by a conduit 16, and the other capsule 14 which is of exactly the same external shape and area, is divided into two compartments one of which 14^a is partly evacuated and the other 14^b subjected internally to exhaust back pressure, being connected to the exhaust pipe 18 by a conduit 17. The outer ends of capsules 13 and 14 are anchored to the walls of the chamber 19 and their inner ends are joined by a member 113, carrying a trunnion 114, on which is pivoted a lever 20. The forked end 120 of lever 20 is pivoted at 22 to a Bourdon tube assembly 23, while lever 20 is pivoted at its other end 121 to the stem 122 of the needle 24. Variations in boost pressure and exhaust back pressure will effect appropriate adjustment of the needle 24 by rocking the pivoted lever 20 about its point of attachment 22 to the Bourdon tube assembly 23. This effects adjustment of the needle 24, under the control of a thermometer bulb 21 in the induction pipe 15, to correct the fuel flow for changes in induction temperature, the lever 20 effecting such adjustment by rocking about the trunnion 114.

With the apparatus as so far described, the fuel flow through the metering orifice 25 will be a substantially linear function of engine speed, and will be appropriately varied to suit changes in boost pressure, induction temperature and exhaust back pressure. The boost pressure is selected by a pilot's throttle lever, not shown, which operates a variable datum boost control device, also not shown, as described in U. S. Patent No. 1,995,800. A lever 52 is coupled to the pilot's throttle lever and operates through a mechanical linkage to effect the further adjustments in fuel flow now to be described.

The pilot's throttle lever is movable from a

slow running position (S. R.) through a cruising range to a full throttle position (F. T.). In the cruising range a weak mixture is desirable for economy. When however the engine power exceeds a given limit, known as the weak-to-normal enrichment point, it is necessary to provide an enrichment in the mixture strength. At slow running the weak cruising mixture is not suitable and an adjustment in mixture strength is required, this being either an enrichment or a weakening according to the type of engine. Thus a weaker mixture is required in the case of engines exhibiting a high degree of boost reversal at or near slow running, while with engines not exhibiting this phenomenon it is desirable to enrich the mixture at slow running. Extra fuel is also required during periods of acceleration. All these requirements are met by a single mechanical linkage controlled by the lever 52, but before explaining how this is done, it will be convenient to explain that additional enrichment of the mixture, beyond the rich mixture corresponding to normal cruising, is required for take off and climb. This is provided by the profiling of the needle 24, the narrower portion 124 of which is operative under these conditions.

The weak-to-normal enrichment is provided by a valve 53 which controls a supplementary conduit 54 in parallel with the metering orifice, the flow through conduit 54 being regulatable by a screw 55 cooperating with a restriction 56. Valve 53 is held closed by its spring 57 when the pilot's lever is in a position between slow running and weak cruising. When the lever is moved to select a power higher than that corresponding to this range, a link 58 connected to lever 52 rocks a lever 59 anticlockwise about a fixed pivot 60, causing a finger 61 on lever 59 to open the valve 53 and enrich the mixture by virtue of the extra fuel supplied through conduit 54.

The slow running adjustment is provided by a valve 62 controlling a supplementary conduit 63 which (when open) provides a flow in parallel with the metering orifice to chamber 19 through a restriction 64 which can be controlled as to area by a screw 65. At slow running the valve 62 is open, as shown, to enrich the mixture. When the lever 52 moves anticlockwise out of the slow running position, a finger 66 thereon moves away from valve 62, allowing a spring 68 to close the valve.

Extra fuel for acceleration is provided, via supplementary conduit 69 by an accelerator pump 70 which is operated, via link 71 and lever 72, which turns on a fixed pivot 73 when and only when the pilot's lever is moved suddenly in the direction to increase the engine power. The lever 72 is connected to a hollow valve 90. When lever 52 is moved in the direction to accelerate, the valve 90 is drawn away from a seating on a diaphragm 159 to allow extra fuel to pass to the engine through conduit 69. Follow-up movement of the diaphragm 159 by spring 160 to close the valve 90 is delayed by a restriction 92, the effective area of which is adjustable by a screw 91. A non-return valve 94 permits of unrestricted movement of valve 90 and diaphragm 159 when the lever 52 is moved to decelerate. The flow through conduit 69 is adjustable by a screw 74 which cooperates with a restriction 75 in the conduit.

The mechanical linkage operated by lever 52 also serves to cut-off the fuel supply from the engine when said lever is moved clockwise from the position shown beyond the slow running

position. A cam 79, carried by an arm 16 pivoted at 17 and connected to arm 59 by a link 18, then forces a plunger 80 up against the action of a spring 81 to close the valve 46 and cut off the fuel supply.

Adjustment for initial tuning purposes is provided by an orifice 41 adjustable by a screw 42, through which a small quantity of fuel may be allowed to by-pass the metering orifice. 82 is a normally closed priming valve through which fuel may be supplied to the engine from inlet 10 by a priming pump prior to starting of the engine. At this time pump 11 is of course inoperative.

In the arrangement shown in Fig. 2, the weak-to-normal enrichment valve 153 controls a conduit 156 for bleeding fuel from the conduit 12 to the suction side of the pump 11. The valve 153 is open, as shown, when the pilot's lever is in a position to select a power requiring weak mixture. When however lever 52 moves anticlockwise to select a power in excess of that corresponding to weak-to-normal enrichment point finger 61 moves away from valve 153, allowing spring 57 to close the valve and so enrich the mixture.

In the case of Figs. 3 and 4, the slow running adjustment is arranged to weaken the mixture at slow running instead of enriching it as in the case of Figs. 1 and 2. In Fig. 3, the slow running valve controls a conduit for bleeding fuel from the inlet of the metering orifice 25 to the suction side of the pump 11. As before, valve 162 is open at or near slow running only, and under other conditions closes to prevent subtraction of the fuel from the main metering supply. The arrangement of Fig. 4 is very similar, but in this case valve 162 controls a conduit 263 for bleeding fuel from the chamber 19 at the exit side of the metering orifice.

What I claim as my invention and desire to secure by Letters Patent is:

1. In a fuel supply system for an internal combustion engine, comprising a main fuel conduit, a variable area metering orifice in said conduit, a fuel pump for feeding fuel under pressure along said conduit and through said metering orifice, means for varying the effective area of said orifice as a desired function of boost pressure, and means for maintaining across said orifice a metering pressure which varies as a desired function of engine speed and thereby controlling the ratio of fuel to air in the mixture supplied to the engine, the combination with a pilot's throttle lever, movable from a slow running position through a weak cruising range to a normal cruising position and beyond to select higher power from the engine, of a first supplementary fuel conduit, a slow running valve for controlling the flow of fuel through said first supplementary conduit, a second supplementary fuel conduit, a weak-to-normal enrichment valve for controlling the flow of fuel through said second supplementary conduit, a third supplementary conduit in parallel with the metering orifice, an accelerator pump for feeding fuel through said third supplementary conduit, all of said supplementary

conduits, when in operation, providing passages alternative to the metering orifice for the fuel supplied by the fuel pump, and a single manually operable linkage controlled by the pilot's throttle lever and arranged to operate both valves and the accelerator pump automatically and as an incident to movement of said lever, and by the resultant control in the flow of fuel through said supplementary conduits to provide an adjustment in the fuel flow at slow running, to give an enrichment in mixture strength on movement of said lever from weak cruising position to normal cruising position, and to provide an enrichment in mixture strength during periods of acceleration.

15 2. Apparatus as claimed in claim 1, in which the second supplementary fuel conduit is in parallel with the metering orifice, and the weak-to-normal enrichment valve is arranged to open to permit fuel to flow through said conduit, only when the pilot's throttle lever occupies a position defined, as to the lower limit of engine power, by the normal cruising position.

20 3. Apparatus as claimed in claim 1, in which the second supplementary fuel conduit serves to bleed fuel from the entry side of the metering orifice, and the weak-to-normal enrichment valve is arranged to open to permit fuel to flow through said conduit only when the pilot's lever occupies a position selecting an engine power less than that required for normal cruising.

25 4. Apparatus as claimed in claim 1, in which the first supplementary fuel conduit is in parallel with the metering orifice, and the slow running valve is open to permit of fuel through said conduit at slow running only, thereby enriching the mixture at slow running.

30 5. Apparatus as claimed in claim 1, in which the first supplementary fuel conduit is arranged to bleed fuel from the entry side of the metering orifice, and the slow running valve is open to permit of fuel through said conduit at slow running only, thereby weakening the mixture at slow running.

35 45 6. Apparatus as claimed in claim 1, comprising a normally open cut-off valve, and a member forming part of said linkage for closing said cut-off valve to interrupt the main supply of fuel to the engine when the pilot's lever is moved beyond the slow running position in the direction to reduce engine power.
